UNITED STATES PATENT OFFICE.

PATRICK MORAN, OF NEW YORK, N. Y.

HEAD FOR BARRELS, CASKS, &c.

SPECIFICATION forming part of Letters Patent No. 296,038, dated April 1, 1884.

Application filed January 26, 1884. (No model.)

To all whom it may concern:

Be it known that I, PATRICK MORAN, of the city, county, and State of New York, have invented a new and useful Improvement in 5 Heads for Barrels, Casks, &c., of which the following is a full, clear, and exact description.

This invention seeks to provide a practical shifting head-plate for all kinds of packages, barrels, casks, &c., which may be quickly and 10 easily removed and put in place for opening and closing the package without removing the hoops, and which, when applied, will close the package air-tight; and the invention consists, principally, in providing the head of the package, in a suitable opening made therein, with 15 a metallic curb, to be used with a plate adapted to be held in and against the curb by a cross-bar and connecting-bolt.

The invention also consists of the construction, arrangement, and combination of parts, 20 all as hereinafter described and claimed.

Reference is to be had to the accompanying drawings, forming part of this specification, in which similar letters of reference indicate corresponding parts in both figures.

Figure 1 is a plan view of a cask or barrel having my invention applied thereto, and Fig. 2 is a sectional elevation of the same.

The body of the package, cask, or barrel A 30 may be of the ordinary or of any improved construction.

In the head B of the cask is formed the opening C, which is elliptical in form, and in this opening is secured by the screws *a a* the curb 35 D, the flange *d* of which fits closely in the opening C, while the outer surrounding flange, *d'*, of the curb comes against the inner surface of the head B, and between this latter flange and the head B is placed the packing E, to form 40 an air-tight joint between the curb and the head B, as will be understood from Fig. 2.

F is the shifting plate. This is of about the same form and external measurement as the curb D, and is formed with the flange *f*, 45 which fits within the curb D, and is provided with the central screw-bolt, G, by which it is adapted to be held in place in the curb D by means of the cross-piece H, through which the bolt G passes, and which bolt receives the nut 50 *b* above the cross-piece H, the said cross-piece H being adapted to span the curb D, as shown

in the drawings. A flat elliptical ring, I, is secured to the outer surface of the head C by the screws *c c*, so as to cover the upper edge of the flange *d* of the curb D, and thus make 55 a nice finish to the head of the package; and upon the shifting plate F is placed the packing J, which, when the parts are in place and the nut *b* screwed down, forms an air-tight joint between the plate F and the flange *d'* of 60 the curb D. The flat ring I also serves as a chafe-plate for the ends *h* of the cross-piece H to rest upon, as will be understood from the drawings.

In use, to open the cask, it is only necessary to remove the nut *b* from the upper end of the bolt G, which will permit the cross-piece H to be removed and the shifting plate F taken out of the cask by passing it edge-wise and endwise through the curb D. To 70 close the cask, it is only necessary to pass the plate F down through the curb D and adjust it on the curb, and then place the cross-piece H upon the bolt G and apply and screw down the nut *b*. In this manner it will be seen that 75 the cask may be very easily opened and closed without removing the head C of the cask, and that the cask will be closed perfectly air-tight, and that the curb-plate and cross-piece are 80 strong, cheap, durable, and practical for their purpose.

Having thus described my invention, I claim as new and desire to secure by Letters Patent—

1. The head B, formed with the opening C, in combination with the curb D, fitted therein, 85 and the shifting plate F, cross-piece H, and bolt G, all arranged to operate substantially as and for the purposes set forth.

2. The curb D, formed of flanges *d d'*, and held in the opening C of the head B, with 90 the packing E placed between the head and flange *d'*, and the shifting plate F, formed with flange *f*, and provided with packing J and screw-bolt G, in combination with the plate I and cross-piece H, for receiving the bolt G, 95 for holding plate F in place for closing the package, substantially as described.

PATRICK MORAN.
